UNITED STATES PATENT OFFICE

127,672

DESIGN FOR A COMBINED SEED DISPLAY AND SALES CABINET

Thomas H. Brown, Grand Rapids, Mich., assignor or to A. J. Brown & Son, Inc., Grand Rapids, Mich., a corporation of Michigan

Application August 8, 1940, Serial No. 94,304

Term of patent 7 years

To all whom it may concern:

Be it known that I, Thomas H. Brown, a citizen of the United States, residing at Grand Rapids, in the county of Kent and State of Michigan, have invented a new, original, and ornamental Design for a Combined Seed Display and Sales Cabinet, of which the following is a specification, reference being had to the accompanying drawing, forming a part thereof, in which:

The figure is a front perspective view of a combined seed display and sales cabinet, showing my new design.

I claim:

The ornamental design for a combined seed display and sales cabinet, as shown.

THOMAS H. BROWN.
